[57] CLAIM

The ornamental design for an integrated transceiver and horn antenna, as shown and described.

DESCRIPTION

FIG. 1 is an isometric view from the front showing the front, top, and right side of our design for an integrated transceiver and horn antenna.

FIG. 2 is an isometric view from the front showing the front, bottom, and left side of our design for an integrated transceiver and horn antenna.

FIG. 3 is an isometric view from the back showing the back, top, and right side of our design for an integrated transceiver and horn antenna.

FIG. 4 is an isometric view from the back showing the back, bottom, and left side of our design for an integrated transceiver and horn antenna.

FIG. 5 is an elevation view from the front of our design for an integrated transceiver and horn antenna showing a second embodiment thereof, the only difference over the first embodiment being that the non-claimed features shown in broken lines on the front surface are shown in solid lines, and therefore make up a part of the claim in this embodiment; and,

FIG. 6 is an elevation from the back of our design for an integrated transceiver and horn antenna.

Additionally, various connectors that may supply power, signal, and provide a test port are shown as broken lines herein. Such connectors are environmental only and form no part of the claimed design. Further, a rectangular lens opening is shown in broken lines in FIG. 2 and FIG. 4. Such lens opening is environmental only and forms no part of the claimed design.

The broken lines on the front face of the first embodiment are for illustrative purposes only and form no part of the claimed design.
